WASHING MACHINE

Kendall Clark, Oakwood, Ohio, assignor to The Murray Corporation of America, Detroit, Mich., a corporation of Delaware

Application December 9, 1947, Serial No. 790,494

7 Claims. (Cl. 68—23)

1

This invention relates to washing machines, and particularly to a washing machine of the completely automatic type in which the clothes are washed, rinsed and wet-dried.

The machine embodies a tub wherein a basket is supported for a wobbling operation by a conic crank; and by a direct drive shaft for a spinning operation with the conic crank released and the basket freely pivoted on a universal joint located on the vertical axis. The conic crank mechanism is mounted on the upper end of a vertical drive shaft having a pulley on the lower end which is belt-driven by a motor. A second shaft, which is tubular in form, surrounds the vertical drive shaft. A brake and clutch are associated with the vertical drive shaft and the tubular shaft for holding the tubular shaft and basket stationary while the crank is operated by the vertical drive shaft and for clutching the vertical drive shaft to the tubular or driven shaft when the crank is disengaged for spinning the basket. The concentric tubular shaft and vertical drive shaft are encased within a tubular housing which is mounted at the bottom in rubber or other resilient material to permit the entire housing, drive mechanism and basket to tilt relative to the base. The bottom of the basket is supported by an inverted cup which is fastened to the top of the conic crank stem. The crank stem extends downwardly from the inverted cup with the upper end secured to a rubber sealing element which functions as a universal joint to permit the conic crank stem to be gyrated while restraining the conic crank stem from rotating so that the basket will be wobbled or progressively tilted. With the universal support of the basket at the top of the driving mechanism in combination with the resilient mounting of the housing on the base, the basket may be spun with minimum precession. Any off-center load will cause the center of the basket to shift laterally from the axis of the spin by an amount sufficient to permit the basket and the unbalanced load to spin about their mutual center of gravity. A plurality of snubbing shoes are provided for frictionally engaging a plate on the housing with a predetermined pressure to provide a resistance to dampen the sway of the housing. A motor is mounted with its axis vertically disposed and shafts extending from each end, the lower shaft having a pulley for driving the belt which drives the pulley on the operating mechanism, and the upper shaft drives the pump impeller. The lint trap, the drain and recirculating valve, and the pump housing are mounted above the motor. The drain and recirculating

2

valves are operated in unison so that when one is closed the other is open for either recirculating the water from the tub to the basket or for directing the water to drain. The solenoid mechanism employed for operating the valves also operates a lever arm which connects and disconnects the brake and the clutch hereinabove referred to. A vacuum breaker is employed in the fresh water intake and the hot and cold water valve is provided with a control knob similar to the control knob on the electrically operated control switch.

Accordingly, the main objects of the invention are: to provide a washing machine which automatically operates through the washing, rinsing and drying cycles which is simple in construction and economical of manufacture; to construct a fully automatic washing machine from a maximum number of stampings and a minimum number of machine parts; to provide a washing machine having a basket which is supported against rotation while progressively tilted or wobbled through a small angle for washing and which is free to have its axis assume a free position during the spinning operation for extracting the water from the washed fabrics; to provide a washing machine with a motor having a pulley on the lower end for driving the mechanism of the machine and which directly supports the pump on the upper end along with the water circulating and drain valves and the lint catching mechanism to form a complete unit.

Other objects and features of novelty of the invention will be specifically pointed out or will become apparent when referring, for a better understanding of the invention, to the following description taken in conjunction with the accompanying drawings, wherein:

Fig. 1 is a broken sectional view of a washing machine which automatically washes, rinses and wet-dries fabrics embodying features of this invention;

Fig. 2 is a plan view of the machine illustrated in Fig. 1;

Fig. 3 is an enlarged sectional view of the structure illustrated in Fig. 2, taken on the line 3—3 thereof;

Fig. 4 is an enlarged sectional view of the structure illustrated in Fig. 2, taken on the line 4—4 thereof;

Fig. 5 is a broken enlarged view of the supporting and driving mechanism shown in washing position;

Fig. 6 is a broken view of the structure illustrated in Fig. 5 when in drying position, and

Fig. 7 is a view of a wiring diagram illustrating the electric circuit employed in the machine.

The washing machine comprises a tub 10 having a lower central opening 11, the edge of which is reversely flanged at 12 to provide an annular channel. A second opening 13 is provided in the bottom of the tub 10, with the edges flanged downwardly at 14 to provide a drain opening. The tub is open at the top with the rim offset inwardly at 15 and further flanged inwardly at 16 to form a support for an annular sealing element 17 which seals the top closure 18 to the top of the tub when the flange 19 thereof extends down over the offset portion 15 so as to have the flange substantially aligned with the peripheral wall 21 of the tub.

The top closure 18 of the tub is provided with a central opening having about the edge thereof a shouldered flange 22 which is reversely bent at the bottom at 23. A door 24, made of molded glass or which may be a stamping or molded from plastics or other material, rests upon the shouldered flange 22. The door is secured to the top cover 18 by a hinge 25 and a recess 26 is provided therein diametrically across from the hinge over which a handle 27 extends. An annular rubber sealing element 28 is supported by the resilience of the rubber around the edge flange 29 of the door for sealing the door to the shouldered flange 22.

Four legs, 31, 32, 33 and 34 are secured to the top of the hub by bolts or other suitable means (not herein shown), and extend downwardly to the floor having adjacent the ends a web 35 for receiving tubular outriggers 36 which are secured thereto by bolts 37 and by adjustable bolts 38, the latter of which have a floor-engaging pad 39 thereon for the purpose of leveling the machine after installation. The four tubular outriggers 36 are welded to the outer flange 41 of a base stamping 42. Inwardly of the flange, the stamping is provided with a downwardly directed shouldered seat 43 and inwardly thereof with a second downwardly disposed shouldered seat 44. An element 45 of resilient material is supported in the shouldered seat 44 of the stamping and secured therein by a washerlike plate 46 which is secured to the shouldered seat 43 by a plurality of bolts 47.

A housing 48 of the operating mechanism comprises a lower tube 49 having an outwardly directed flange 51 at the bottom which is secured by bolts 52 to a bottom casting 53. The flanges 51 and that on the casting 53 extend into a slot 54 in the resilient element 45 to provide a resilient universal mounting for the housing 48 and the operating and supporting mechanism contained therein. The casting 53 supports a bearing 55, herein illustrated as of the ball type, for supporting a driven element 56 for rotation about a vertical axis. An annular washer 57 is secured to the bottom of the casting by screws 58 for retaining the bearing 55 thereon. A pulley 59 is secured to the end of the driven element 56 by a nut 61, the main body portion 62 of the pulley being offset upwardly so that the peripheral V edge 63 thereof is substantially aligned with the bearing 55.

A sealing element 64 is disposed about the driven element 56 for providing a seal thereabout. The sealing element embodies a pair of members 65 and 66 which are free to rotate relative to each other while providing a seal through their engaging surfaces which are urged toward each other with a predetermined pressure by a spring

67 disposed about a resilient bellowslike sealing element 68. The upper element 65 carries an O-ring 69 which seals the top of the element to the driven shaft 56. The shaft 56 is provided with a pair of diametrically projecting arms 71 on which rollers 72 are mounted. The rollers operate in a slot 73 in an inverted cup element 74. The rollers permit the vertical shifting of the cup relative to the rollers with a minimum amount of friction, thereby requiring a minimum amount of applied force to change from one cycle of operation to another.

The cup is secured to the end of a tubular drive shaft 75 by a nut 76 secured thereto by a locking washer 77. A stem 78 projects upwardly on the axis of the driven shaft 56 in a position to abut against a spring 79 mounted within the tubular drive shaft 75. The upper end of the spring abuts against a washer 81 which engages a pin 82 extending through the shaft 75. A seat 83 on the end of the stem 78 projects within the lower end of the spring, which end abuts against a head 84 on the upper end of the stem 78, the outer surface of which is of arcuate shape to have a line contact with the inner surface of the shaft 75.

The collar 79 on the lower end of the shaft 75 has a thrust plate 85 disposed thereabout on a thrust bearing 86, resting on a plate 87 disposed adjacent to the bottom of the cup 74. A lever 88 has a pair of spaced fingers 89 provided with contact tips 91 which span the shaft 75 and rest upon the thrust plate 85. A series of clutch plates 93 have inwardly projecting fingers which extend within slots 90 extending upwardly from the end of the tubular driven shaft 92, and a second series of plates 94 have outwardly projecting fingers which project into slots 95 in a cup-shaped element 96 welded to the upper end of the housing 49. A plate 97 is carried by the bottom of the tubular shaft 92, having arcuate slots near a central aperture through which the wall of the driven shaft 92 between the slots 90 thereof projects. The plate 97 is urged upwardly to provide engagement between the two series of plates 93 and 94 by a conical spring 98 which is supported on the bottom of the tubular shaft 92 by a snap ring 99.

The tubular shaft 92 is recessed at 101 and carries longitudinally split bearings 102 and 103 having projections 104 which extend into the diametrically disposed apertures 105 in the tubular shaft 75. The bearing elements 102 and 103 rotate and reciprocate with the driving shaft 75 on the inner surface of the recessed portion 101 of the tubular shaft. A sleeve 106 is welded or otherwise secured to the cup-shaped element 96 about the tubular driven shaft 92 to form the upper part of the housing on which a plate 107 is welded or otherwise secured. A casting 108 is welded to the top of the plate 107 located thereon by fingers 110 stamped from the plate. The casting supports a ball bearing 109 secured against longitudinal movement on the shaft 92 by a pair of snap rings 111 and 112. A sealing element 113 seals the upper end of the shaft 92 to the inner surface of the casting 108, the sealing element being similar to the seal 64 at the lower end of the driving mechanism. A sleeve bearing 114 is provided between the upper end of the driving tubular shaft 75 and the driven shaft 92.

The upper end of the shaft 92 is flanged outwardly at 115 and is welded or otherwise secured to a cup-shaped member 116. The cup-shaped member 116 has an inner conical clutch surface

117 which is mating with the outer cup surface 119 on a driven cup 121 on the upper end of the driving shaft 75. A cone clutch is formed between the two surfaces 117 and 119 when the shaft 75 is in lowered position for driving from the central shaft 75 through the outer shaft 92 to drive the basket in rotation. A sleeve 122 has a flange 123 at its lower end which is secured by bolts 124 to a flange 125 on the cup 116 with a sealing gasket 126 therebetween. A universal element 127 provides universal movement to the basket and is secured to the upper end of the sleeve 122 by screws 128. The universal element 127 comprises an outer collar 129 and an inner collar 131 joined by a resilient web 132 which is made of rubber or like material and which is bonded to the sleeves. The sleeves are provided with apertures 133 into which the material of the web 132 may project to increase the resistance to rupture due to the torsional strains between the bonded surfaces.

20 A crank stem 134 is secured to an inverted cup-like element 135 after the sleeve 131 has been placed over the end thereof. The sleeve has notches 136 in the end which project over the ends of a pin 137 extending through the stem 134. A nut 138 secures the inverted cup-like element 135 on the upper end of the stem. A basket 139 is supported on a flange 141 on the bottom of the inverted cup element 135, being secured thereto by a plurality of bolts 142 which draw the inner flange 143 of the basket downwardly against a sealing gasket 144 and the flange 141 to form a water-tight joint. An inverted cup 145 is secured over the inverted cup 135 to the top of the stem 134 by a screw 146. The entire housing, that is to say, the interior of the sleeve 48, sleeve 106, cup 116 and the lower portion of the sleeve 122, is filled with lubricating oil through the stem 134, the sleeve 122 or through an aperture 147 in the resilient material 132 which is of sufficient size to permit a probe to be inserted therein to ascertain the height of the oil and which is closed by a plug 148. It is to be understood that a high and low plug could be employed in the sleeve 122 as is conventional practice.

30 A flexible sealing element 149, of rubber or like composition, is sealed to the bottom of the tub by a ring 151 which forces the annular flange at the bottom of the element in the channel of the annular flange 12. A sealing ring 152 seals the inner flange of the element 149 to the casting 108 on the upper end of the housing.

40 The lower end of the stem 134 is provided with a mushroom head 153 having a shaft 154 rotatable within a bearing sleeve 155 and operating against a thrust bearing 156. The shaft 154 has a stem 157 on its upper end on which a sleeve 158 is supported. Apertures 159 extend through the bearing sleeve 155 and the sleeve 158 in which setscrews 161 are threaded for retaining the mushroom head 153 on the end of the stem 134. A washer 162 is secured to the end of the stem 157 by suitable means, herein illustrated by peening over the end to form the head 163. Apertures 164 may be provided through the stem 134 and bearing sleeve 155 to provide passageways for lubricating the shaft 154.

50 The cup 121 has a forged driving element 165, which may be hard steel or the like, secured thereto by one or more rivets 166. The upper end of the driving shaft 75 has a plug 167 welded or otherwise secured therein. The plug has an enlarged cylindrical head 168 extending therefrom above the shaft end which is provided with

5 a flat surface 169 to form a driving D-shaped extension having a threaded stud portion 172 on the top thereof. The cup 121 and forging 165 are secured by a nut 171 to the threaded stud portion 172 in driving relation therewith. An aperture 173 is provided through the plug 167 to permit the liquid within the driving shaft 75 to readily flow therethrough when the shaft 75 is moved longitudinally. The upper end of the threaded stud portion 172 is sloped at 174 to force the stem 134 to deflect and to contact the forging 165 when the cup is raised. The forging is provided with a recess 175 the shape of the mushroom head 153 which projects therein when the cup is raised in driving relation therewith. To assure the connection of the mushroom head with the recess 175, a recess 176 spirals outwardly from the recess 175 to the wall of the cup so that should the end project within the region of the spiral it will be directed into the recess 175 during the first partial revolution of the cup relative thereto.

30 The basket 139 has a bottom portion 177, the central portion 178 of which is of inwardly projecting conical form terminating in a flange 143 about a central opening which bolts upon the flange 141 of the cup-shaped element 135. An inwardly projecting top portion 181 of the basket is of smaller diameter than the diameter of the portion 177 and is provided with spaced offset areas 182 which engage the portion 177 and are welded thereto. This provides openings 183 around the top of the bottom portion 177 from which the water may be expelled during the spinning operation. A series of vertically disposed apertures 184 are provided in the wall of the bottom portion 177 and several drain holes 185 are located adjacent to the central conical portion 178. The top of the top portion 181 has a central opening for the reception of the fabrics to be washed, the inner edge being reversely flanged at 186.

40 A supporting plate 187 is secured to the base plate 42 by bolts 188 and is braced to the tub 10 by an element 189 secured to a bracket 191 on the tub bottom by a bolt 192. Several brackets 191 are provided on the bottom of the tub from which spring arms 193 project having snubbing shoes 194 secured thereto for engaging the under surface of the plate 107. The snubbing shoes 194, acting against the plate 107, dampen out any tendency of the supporting housing and drive mechanism to produce a sway thereto as the speed of rotation of the basket is built up from zero to maximum. The input energy which would produce this harmonic build-up of sway is taken out by the snubbing action of the shoes 194 on the plate 107 as the surfaces 117 and 119 slip relative to each other as the spinning speed of the basket is built up. When the speed builds up to and beyond the natural frequency of the system, which will be somewhere between the zero and maximum speed, this tendency to produce an increasing sway to the housing and basket on the resilient element 45 will no longer exist and the basket and housing will assume a normal spinning position depending upon the distribution of the clothes within the basket. Since neither the plate nor the shoes are a portion of the operating part of the system, no direct energy from the motor to the basket is being absorbed thereby. It is only the energy dissipated between the mating surface of the cone clutch during the time of slippage which is being dampened out by the snubbing shoes.

50 A thermostatically controlled fresh water valve

195 is mounted on the plate 187, having intake ports 196 and 197 to which hoses are connected from fresh hot and cold water sources. A drain hose 198 is also supported by the plate 187, being connected to the outlet 199 of the water pump 201. A motor supporting bracket 202 is also mounted on the base 42 for supporting a motor 203 with its axis in a vertical position. On the bottom end of the motor shaft 204, a pulley 205 is keyed or otherwise supported in driving relation, having the V groove thereof aligned with the V groove 63 of the pulley 59 secured to the drive shaft 56. A belt 206 connects the pulleys 205 and 59 in driving relation.

The upper end of the shaft 204 supports the pump vane 207 while the motor housing supports the drain valve and housing assembly 208. The vane 207 has a hollow interior 209 in which a sealing element 211 is mounted, the sealing element being the same as the sealing element 113 above referred to which positively seals the shaft to the housing 212 of the pump. While it is not contemplated that any leak can occur through the sealing element 211, for precautional measures shrouds 213 and 214 are mounted on the motor to prevent any water which may leak by the shaft from damaging the motor windings. The pump housing is provided with two valve openings 215 and 216 in which valves 217 and 218 are mounted on stems 219 and 221, respectively. The stems are secured to a U-shaped operating lever 222 having a bracket 223 thereon connected to an operating rod 224. The operating rod is pivoted to a lever 225 which is pivoted to a bracket 226 on the motor supporting bracket 202. The end of the lever 225 is secured to the end of an armature 226 operating within a solenoid 227 which is supported on the motor supporting bracket 202.

The shift lever 88 of the operating mechanism passes through a bushing 228 which is welded or otherwise secured to the tubular portion 49 of the operating mechanism housing. A resilient bellowslike sealing element 229 encompasses the lever 88 and the bushing 228 to seal the area about the lever against the passage of a fluid. A bracket 230 is mounted on the tubular portion 49 of the housing 48, having pivoted thereon a bell crank 231, the extending arm 232 of which is connected by a spring 233 to the end of the armature 226. A roller 234 on the bell crank 231 engages a plane face 235 of the lever 88 and causes it to rock on the pivot 236 supported by the bushing 228. When the solenoid is operated, both of the valves 217 and 218 are shifted, one to closed and one to open position, and the lever 88 is rocked to operate the driving mechanism to one or the other position.

A second outlet port 237 is provided on the pump housing 208 for connection to a recirculating nozzle 238, illustrated in Fig. 3. A delivery port 239 on the thermostatically controlled hot and cold water valve is connected by a conduit 241 to a nozzle 242 which has an antisiphon device 243 interposed in the circuit. The antisiphon device embodies a receptacle 244 having opposite walls containing an opening 245 and the adjacent walls connected to the intake port 246 and the flared end 247 of the nozzle 242. Water under pressure delivered from the port 246 is directed into the flared end 247 of the nozzle and is thereby delivered into the tub 10. Any drainage which may occur into the receptacle 244 is directed into the tube through the drain tube 248. The antisiphon device prevents any wash water, soap suds

and the like from draining back into the delivery conduit should a suction condition occur therein.

A pair of depending brackets 249 extends downwardly from the front portion of the tub on which a cover plate 251 is hinged to drop downwardly to permit a lint drawer 252 to be removed forwardly of the machine. The lint drawer is secured in sealed position by a U-shaped element 253, having its end pivoted on brackets 254 supported on the side of the housing 208. The upper end of the housing is provided with a seal 255 which engages the bottom of the tub about the drain opening 13 and seals the housing thereto. A locking element 266 is pivoted on the front end of the door on the pivot 257 and is provided with a hook 258 at the bottom which engages the web of the element 253. When the hook 258 is pivoted downwardly, the element 253 is released from the hook 258, permitting the drawer to be withdrawn. The drawer has a central outlet opening 259 over which a semispherical drain screen 261 is disposed. The ledge 262 provided on the inside of the drain screen outwardly of the drain opening 259 catches the lint which passes through the drain screen 261 due to the centrifugal action of the water beneath the screen. This lint is removed periodically through the removal of the drawer from the housing in the manner described above. A sealing element 263 is provided about the front edge of the drawer for sealing the drawer in closed position. It will be noted that the valves 217 and 218 open toward the drain outlet so that any string, pieces of cloth and the like which pass through the pump to drain or through the recirculation system cannot accumulate about the valve or valve stems which are disposed out of the path of flow of the water.

The four legs on the tub are utilized for housing the fresh water and recirculating nozzles, the control switch for operating the machine through its wash, rinse and wet-dry cycles and the mechanism for adjusting the hot and cold water valve. The leg 31 houses the control switch and has on the top thereof the control knob 265 which is adjusted to set up the operating cycle and advanced by a motor in the switch. The motor and switch are of conventional form, the one employed with the herein described machine having three contacts thereon operated by cams. The leg 34 has a dial 266 on the top thereof connected to mechanism for adjusting the thermostatically operated intake valve 195. The leg 33 has conduits therein which are connected to the nozzles 238 and 242, respectively. It is to be understood that one or the other of the nozzles may be placed in leg 33, although in the arrangement herein illustrated the leg 33 has no mechanism therein.

Panels 267 may be secured between the legs to form a completely enclosed cabinet which can be sold as a deluxe model. For the ordinary model with the panels 267 eliminated, a trim band 268 of chromium or the like may be applied to the bottom of the tub. In such an arrangement, a U-shaped closure panel 269 is applied about the motor and drive mechanism secured to the supporting plate 187 by screws 271.

Referring to Fig. 4, the hinge for supporting the glass cover 24 embodies a wing 272 secured by a pivot 273 to a wing 274 which is secured to the cover. The wing 274 and a plate 275 have projections forming a stop arm, the wing and plate being secured to the cover by a pair of bolts 276. An element 277 is then snapped over the hinge to provide a cover therefor. A rubber bumper 278 may be provided on the end of the stop arm

which strikes a stop plate 279 secured to the inside of the top element 18 by bolts 281 which secure the wing 272 to the flange 282 on the top cover. The pocket 26 in the glass cover is preferably provided with a hole 283 for venting the inside of the tub when the door 24 is sealed thereon to permit air to pass into or from the tub when the water passes to drain or is introduced into the tub. The glass cover plate 24 is provided with five openings which are molded therein, two for the bolts of the handle 21, two for the bolts of the hinge and one in the pocket 26. It will be noted further that a lip 284 is provided around the outer lower edge of the cover to project within a recess 285 in the rubber sealing element 28 for retaining the sealing element on the peripheral edge thereof. From Fig. 3 it will be noted that rubber grommets 286 are provided around the nozzles for sealing the nozzles to the top element 18 of the tub.

Referring to Fig. 7, a wiring diagram is illustrated comprising a main circuit composed of conductors 291 and 292 in the former of which a main control switch 293 is disposed. This is the switch referred to hereinabove to which the indicating knob 265 is secured. The conductor 292 has a switch 294 in series therein which, as illustrated in Fig. 1, has an actuating arm 295 carrying a roller 296 disposed in the path of sway of the basket 139. This switch is available during the spinning operation for disconnecting the entire electric circuit if, for some reason, the sway should become so great as to move out of a permissible area of spinning.

A circuit 297 connects the motor 203 across the conductors 291 and 292. A circuit 298 connects a motor 299, which drives the main control switch 293, across the conductors 291 and 292 of the main circuit. A circuit 301 is connected to the conductor 291 and to a single pole double throw switch 302. A circuit 303 from one pole of the switch 302 is connected to a single pole double throw switch 304. One pole of this switch is connected by a circuit 305 to the hot water solenoid 306 of the fresh water solenoid valve 195 and to the conductor 292. A circuit 307 from the other pole of the switch 302 connects the mixed water solenoid 308 of the fresh water solenoid valve 195 to the circuit 292. A circuit 309 connects the other pole of the switch 303 to the circuit 307 ahead of the solenoid 308.

A circuit 311 is connected through a switch 312 to the solenoid 227 and through a cover safety switch 313 to the circuit 292 from the circuit 291. This switch is illustrated in Fig. 4 as having a plunger 314 which is moved inwardly to "on" position when the cover 24 is in closed position and which moves to open circuit position when the cover is open to deenergize the solenoid 227 and shift the basket operation from spinning to wobbling as a safety feature. If the cover is closed when the control switch 293 is set for spinning operation, the shifting of the contacts in the switch 313 to "on" position energizes the solenoid 227 and the basket shifts into spinning operation.

The main switch 293 is provided with three contacts and a series of cams which operate the contacts to open and closed positions. It will be noted that it is only necessary to shift the switch or contacts 312 of the switch 293 from closed to open position to change the operation of the basket from spinning to wobbling and at the same time to change the position of the valves 217 and 218 from drain to recirculating position. The contacts of the switch 293, illustrated as

switches 302 and 304, controls the introduction of the fresh water into the tub through the operation of the specific cams employed for movement into engagement therewith. This main valve control switch and solenoid operated valve, being of the conventional form, are not illustrated herein in detail.

When operating the machine, the fabrics to be washed are placed within the basket 139. The control knob 265 is then moved from "off" position to "wash" position, at which time water from the thermostatically operated valve 195, which is a constant flow valve, will be introduced through the nozzle 238 into the basket. At the same time the motor 203 is energized and the solenoid 227 remains de-energized, with the valves 217 and 218 in the position illustrated in Fig. 1. This is the position in which the water will be recirculated from the tub through the nozzle 242 into the basket 239 from which it will drain into the tub and continue by recirculation. The water will be admitted to the tub for two minutes and will fill substantially to the line 287, after which the supply is shut off. The operation of the motor drives the driving shaft 75 with the brake clutch 93 engaged to prevent the driven shaft 92 from operating. This prevents the basket from rotating while the crank stem 134 has the mushroom head 153 driven in rotation by the cup 121. The mushroom head rotates within the end of the stem so as to eliminate wear in the pocket 175 of the forging 165 in which the head rests during the washing operation. This causes the basket to wobble and the clothes to be agitated in the presence of a predetermined amount of water within the basket provided by the recirculating system. The bottom of the basket may be provided with vanes 288 which cause a progression of the clothes within the bottom during the washing operation.

After the passage of a sufficient amount of time, approximately ten minutes, the solenoid 227 is actuated to tilt the lever 88 in a clockwise direction, moving the shaft 75 downwardly to cause the cone surfaces 117 and 119 to engage and the brake clutch 93 to be released to permit the shaft 92 to be driven with the driving shaft 75. The end of the bearing 103 on the driving shaft 75 strikes the portion 289 of the plate 97 between the shafts 75 and 92 and relieves the series of plates 93 and 94 from the pressure of the spring 98. This downward movement of the shaft 75 releases the crank stem 134 to permit the stem to assume a vertical position during the spinning of the basket which now occurs. The solenoid actuation also shifts the valves 217 and 218 to close the former and open the latter so that the water may flow from the tub into the drain. Thereafter, to provide for the rinsing of the clothes, fresh water is delivered into the basket through the nozzle 238 for one minute, after which the solenoid 227 is shifted to interrupt the spinning operation and to again wobble the basket as in a washing operation while the water is recirculated. After two minutes, the solenoid 227 is again actuated to spin the basket and to drain the water from the tub. This cycle is again repeated, spinning the basket for one minute while fresh water is introduced into the basket and then the basket is wobbled while the water is recirculated for a period of two minutes. Thereafter the basket is spun for a period of approximately two minutes to extract the greater part of the water from the clothes and wobbled for one minute to redistribute the clothes in the basket.

The basket is operated for approximately 500 R. P. M. in the washing, rinsing and drying cycles, although a greater or less speed may be employed. It was found at this speed that approximately one pound of water remained in each pound of clothes after the extracting operation. It will be noted that the entire operating mechanism and basket are supported in the resilient element 45 so that the entire mechanism is free to tilt, and further, that the basket is supported on the rubber web 121 which permits it to assume a tilt to a desired spinning position depending upon the distribution of the fabrics within the basket. The supporting housing and driving mechanism may tilt out of a vertical position to offset any unbalanced load within the basket 139 as the axis of the basket is free to assume a vertical position or a tilted position relative to the vertical to be at an angle to the axis of the driving mechanism and supporting housing. When the main control switch 293 reaches its off position, the electric circuit is entirely disconnected, the solenoid 227 de-energizes and the operating mechanism is then in a position to begin another cycle of operation when the knob 265 is shifted to on position. It is to be understood that the tension in the spring 79, compressed during the downward movement of the shaft 75 by the lever 88, is available upon the release of the solenoid to move the shaft 75 upwardly to engage the crank cup 121 with the crank stem 134 and move the bearing 103 out of engagement with the portion 289 of the plate 97 to permit the spring 98 to engage the series of clutch plates 93 and 94. It is to be understood that a similar series of plates 93 and 94 may be substituted for the cone clutch provided by the engaging surfaces 117 and 119 to provide a more positive drive during the spinning operation.

What is claimed is:

1. In a washing machine, a tub, means for supporting said tub, a drive mechanism projecting upwardly through said tub mounted for resilient movement at the base and embodying a central and a tubular shaft, a basket within said tub, a crank stem extending from the bottom of said basket, a resilient sealing and universal element securing said stem to the tubular shaft, crank means secured to the central shaft for operating said stem when said crank means is moved upwardly into engagement therewith for wobbling the basket by flexing said resilient material forming the universal element, means for raising and lowering said central shaft, and means for connecting said central shaft to said tubular shaft when the central shaft is moved downwardly from engagement with said stem for rotating said tubular shaft and basket.

2. The combination in a washing machine, of a tub, a base for said tub, a basket in said tub, a tubular shaft having at the top a resilient element, a stem on the basket passing through said resilient element for supporting said basket, a central shaft within said tubular element having a cup on the upper end engageable with the end of the stem, a housing encasing said tubular shaft, resilient means for mounting said housing at the bottom to the base of the tub, drive means for said central shaft comprising a stem having a shaft disposed normal thereto provided with a pair of rollers, a cup on the central shaft having a slot in which said rollers operate, brake means for engaging said tubular shaft when said central shaft is operating when in raised position, means for raising and lowering said central shaft,

and means for disengaging said brake means and clutching said central shaft to said tubular shaft when said central shaft is moved downwardly.

3. The combination in a washing machine, of a tub, a base for said tub, a basket in said tub, a tubular shaft having at the top a resilient element, a stem on the basket passing through said resilient element for supporting said basket, a central shaft within said tubular element having a cup on the upper end engageable with the end of the stem, a housing encasing said tubular shaft, resilient means for mounting said housing at the bottom to the base of the tub, drive means for said central shaft comprising a stem having a shaft disposed normal thereto provided with a pair of rollers, a cup on the central shaft having a slot in which said rollers operate, brake means for engaging said tubular shaft when said central shaft is operating when in raised position, means for disengaging said brake means and clutching said central shaft to said tubular shaft when said central shaft is moved downwardly, means for raising and lowering said central shaft, and a solenoid for operating said raising and lowering means.

4. In a washing machine, a tub, means for supporting the tub, drive mechanism beneath said tub embodying a shaft, a basket within said tub, a downwardly projecting stem on the bottom of said basket, a rotatable support about said shaft, a resilient element for securing said stem to said rotatable support, crank means on said shaft engageable in one position with the end of the stem for wobbling the basket through the flexing of said resilient element, and means for retaining the basket and rotatable support against rotation when the basket is being wobbled.

5. In a washing machine, a tub, means for supporting the tub, drive mechanism beneath said tub embodying a shaft, a basket within said tub, a downwardly projecting stem on the bottom of said basket, a rotatable support about said shaft, a resilient element for securing said stem to said rotatable support, crank means on said shaft engageable in one position with the end of the stem for wobbling the basket through the flexing of said resilient element, brake means for restraining the basket and rotatable support against rotation, and means for moving said shaft downwardly for disconnecting said crank means from said stem and connecting the shaft to said rotatable support for driving said basket in rotation, with the basket free to assume a substantially horizontal position.

6. In a washing machine, a tub, means for supporting the tub, drive mechanism beneath said tub including a shaft, a basket within said tub having a downwardly projecting stem on the bottom, a resilient element for mounting said stem on a rotatable support, crank means engaging the end of the stem for wobbling the basket through the flexing of said resilient element, brake means for restraining the basket and rotatable support against rotation, means for moving said shaft downwardly for disconnecting said crank means from said stem and connecting the shaft to said rotatable support for driving said basket in rotation, with the basket free to assume a substantially horizontal position, a housing encompassing said rotatable support, resilient means engaging the base of said housing permitting it to tilt relative to the tub, and snubbing means engaging said housing for preventing undue precession of the basket when being

accelerated up to and beyond its critical speed in rotation.

7. In a washing machine, a tub, means for supporting the tub, drive mechanism beneath said tub including a shaft, a basket within said tub having a downwardly projecting stem on the bottom, a resilient element for mounting said stem on a rotatable support, crank means engaging the end of the stem for wobbling the basket through the flexing of said resilient element, brake means for restraining the basket and rotatable support against rotation, means for moving said shaft downwardly for disconnecting said crank means from said stem and connecting the shaft to said rotatable support for driving said basket in rotation, with the basket free to assume a substantially horizontal position, a housing encompassing said rotatable support, resilient means engaging the base of said housing permitting it to tilt relative to the tub, snubbing means engaging said housing for preventing undue precession of the basket when being accelerated up to and beyond its critical speed in rotation, and means for interrupting the spinning operation of

the basket when the precession exceeds a predetermined amount.
